GAS BURNER CONTROLLING MEANS

**Earnest J. Dillman and Jack E. Fleury, Detroit,
Mich., assignors to Detroit Lubricator Com-
pany, Detroit, Mich., a corporation of Michigan**

Application April 20, 1945, Serial No. 589,414

14 Claims. (Cl. 158—125)

1

The invention relates generally to automatically operated valve means for controlling the flow of fluid, and it has particular relation to the control and burning of fuel in a heating system.

One object of the invention is to provide an improved automatically operating valve which is actuated in predetermined relation to a pilot valve.

Another object of the invention is to provide as an article of manufacture, an improved valve arrangement for controlling the flow of fuel and which includes a main valve control and a pilot valve control arranged in a compact structure readily connectable to a fuel supply line.

Another object of the invention is to provide an improved valve arrangement for controlling the flow of fuel and for igniting the same through the use of electrical ignition.

Other objects of the invention will become apparent from the following specification, from the drawings relating thereto, and from the claims hereinafter set forth.

For a better understanding of the invention, reference may be had to the drawings wherein:

Figure 1 is a view, generally diagrammatical, illustrating an arrangement constructed according to one form of the invention for controlling the flow and burning of fuel in a fuel burning apparatus;

Fig. 2 is a vertical section of a valve arrangement forming part of the invention as seen substantially along the line 2—2 of Fig. 3;

Fig. 3 is a cross-sectional view taken substantially along the line 3—3 of Fig. 2;

Fig. 4 is a cross-sectional view taken substantially along the line 4—4 of Fig. 2;

Fig. 5 is a cross-sectional view taken substantially along the line 5—5 of Fig. 4;

Fig. 6 is a cross-sectional view taken substantially along the line 6—6 of Fig. 4;

Fig. 7 is a detail view of the lower part of the pilot valve showing the seat, inlet and outlet; and,

Fig. 8 is a cross-sectional view taken substantially along the line 8—8 of Fig. 7.

Referring to Fig. 1, the general features of the present invention will be more readily understood through reference first to different parts of the arrangement and briefly setting forth the manner in which such parts function and co-operate. In the first place, gaseous fuel is supplied through a main line connected to an inlet 9 of a main valve 10, and from this valve the gas flows through a line 11 to a main burner 12. The main valve includes a separating wall 13 having an inlet or valve opening 14 which is adapted

2

to be closed or opened by a valve member 15. The main burner is adapted to be ignited by a pilot 17 which is at the end of a fuel line 18, and the supply of fuel to this pilot is controlled by a pilot valve indicated diagrammatically at 19.

Ignition of the pilot is effected by electrical igniting means indicated at 20 which is in the secondary circuit 21 of a transformer 22. The primary in this transformer indicated at 23 is shown in the circuit of a room thermostat 24, and for the purposes of simplicity, both the primary 23 and thermostat 24 are shown as connected to ordinary house circuit lines indicated by wires 25 and 26. The primary 23 and thermostat 24 are also in series circuit with the primary 28 of a transformer 29 shown as adjacent the pilot valve 19. The secondary 30 of the transformer 29 is in the circuit of a heat motor 31 which acts to control the pilot valve as hereafter will be considered in greater detail.

Prior to describing parts of the valve controlling device, it might be mentioned briefly that when the thermostat 24 closes so as to require heat, the circuit is closed through the electrical ignition 20 and sparking occurs across the ignition points as will be readily understood. At the same time, the pilot valve 19 will open to allow flow of gas to the pilot 17, and as a result, the pilot 17 is lighted. As the pilot heats up, a bulb element 32 attached to the side of the pilot, automatically effects operation of a bellows device 33 to open the main valve 10, and as a result gas flows to the main burner 12 and is ignited by the pilot. Operation of the main burner continues until thermostat 24 opens the circuit through the primary 28. As soon as the circuit through the primary 28 is opened, the heat motor 31 cools, the pilot valve closes, the pilot 17 cools, and in turn the main burner valve 10 closes. This brief description is merely intended to provide initial understanding of the invention in a general way so that a detailed description of the valve arrangement in the succeeding figures will be perhaps better understood as the description proceeds.

Now referring to Fig. 2 in particular, the main valve 10 including the valve element 15 embodies the same structural features as are embodied in the copending application of Earnest J. Dillman, Serial No. 445,571, filed June 3, 1942, now Patent 2,409,112, and therefore, it would seem needless to refer to this structure in full detail. Briefly, however, it may be stated that the valve seating element includes a stem 34 which is reciprocatory in a vertical direction through an

upper cover part 35 of the valve casing, and which is secured thereto. A flexible diaphragm 35^a is sealed to the stem 34 and to the casing to prevent leakage of gas. The upper end of the stem is slidably mounted in a collar 36 anchored in a frame 37 projecting upwardly from the cover 35, and below the collar the stem 34 passes through and is fastened to a sleeve 38 having disk portions 39 and 40 integral or rigid with its ends. The lower disk portion 40 serves as an armature which is immediately above a stationary permanent magnet 42 having an opening at its center allowing the valve stem to move therethrough. The magnet normally acts to hold the armature 40 in its lower position and to hold the main valve closed.

At one side of the post 37, a control device 43 including a bracket 44 is pivotally anchored on the cover 35 as indicated at 45, and this bracket carries an arm 46 having a roller 47 disposed between the two flange or disk portions 39 and 40 on the sleeve 38. Upward movement of the arm 46 is opposed by a spring 47^a. The construction of the parts to which reference has thus far been made, is the same as the construction disclosed in the said copending application for patent, Serial No. 445,571, filed June 3, 1942, now patent 2,409,112, and it would seem needless to describe all the details here. It would seem sufficient to say if external means (presently to be described) is provided to move the sleeve 38 upward against the action of the magnet 42, that as soon as the moving force becomes sufficient, the valve will quickly and partly open against the magnetic force and the lower disk portion will then strike the roller 47 and slowly move the arm 46 upward against the force of spring 47^a thereby continuing the opening movement of the valve member 15.

The valve structure so far described extends upwardly into a housing or casing 50 which includes two laterally disposed parts 51 and 52 having, as best shown by Figs. 2, 3, and 4, base portions 53 and 54. An opening 55 in the base portion 53 allows the valve structure described to project upwardly into the casing, and the valve cover 35 is secured to such base portion by screws 56. The base portion 54 is disposed on the base portion 53 and is releasably secured thereto and to the cover 35 by means of oppositely disposed bolts 57 which are threaded into the cover. These bolts extend through open ended notches 58 and 59 in the end of the base portion 54 so as to permit ready separation of these two parts of the casing. Also, for accommodating the valve structure, the base portion 54 has a recess or opening 60 corresponding to a part of the opening 55 in the base portion 53.

At their opposed ends, the two parts 51 and 52 of the casing have upright end walls 64 and 65, and along the edges of the base portion 53, upwardly directed short flanges 66 and 67 are provided. The casing is completed by means of a U-shaped closure or cover 68 which has side walls extending downwardly so as to complete the sides of the casing and short downwardly directed end flanges 69 and 70 which are fastened to the upright walls 64 and 65 by screws 71. From this it follows that a readily separable casing is provided for housing the valve structure.

The external means mentioned for opening the valve comprises, as best shown by Figs. 1, 2, and 3, a plate type lever or arm 72 which is fulcrumed on a pin 73 extending through ears 74 and 75 on the lever. In turn, the pin is supported at its ends in legs 78 and 79 of a bracket 80 secured to

the end wall 65 on part 52 of the casing by screws 81 passing through the base of the bracket. Tongues 82 and 82^a are provided on leg 79 and rest on the base portion 54 of the casing, and rivets 83 provided on the tongues have locating relation to openings 84 in such base portions as seen in Fig. 4. The lever 72 at its inner end 85 extends between the disk portions 39 and 40 on sleeve 38 so that if the lever is swung vertically it will shift the sleeve and move the valve stem 34. It will be noted that the inner end of the lever has a downwardly turned lip 86 so that if the valve member 15 sticks in open position when the lever starts to move downwardly, it will almost immediately contact the armature 40 and force the valve member to closed position.

Movement of the lever 72 about its fulcrum is effected by means of the bellows device 33 which includes a casing 88 secured to the wall 65 by the screws 81 and a bellows 89 within the casing which is fastened to a thrust member or pin 90. This pin extends through openings in the wall 52 and bracket 80, and has a conical end 91 which seats in a conical seat 92 formed in a depending leg 93 on the lever 72. Collapsing of the bellows moves the lever 72 in a clockwise direction as seen in Fig. 1, so as to effect opening of the main valve while return movement of the bellows allows the valve to close. This return movement is effected by means of a spring 94 within the casing 88 which is disposed around pin 90.

The bulb 32 previously mentioned, is connected by a tube 95 and coupling 96 to the casing 88, and the casing externally of the bellows as well as the tube 95 and bulb 32 contains a volatile fluid so that upon heating of the fluid in bulb 32, the bellows will collapse and then upon cooling of the fluid the bellows will expand through action of the spring. The rear of the bellows may be open to atmosphere along the end of pin 90 so as to allow air to escape and enter as will be readily understood. From this, it should be evident that if the pilot light 17 is ignited, the bulb 32 will become heated and as a result, the main valve will open. It will also be evident that as the pressure against the lever effected by the bellows device increases, it finally overcomes the magnetic force acting to hold the valve closed, until a substantial force is built up and which is sufficient to overcome the magnetic force. As soon as this magnetic force is overcome, the valve member 15 is quickly and forcefully opened so as to allow a partial supply of gas to the main burner 12 which will then ignite since the pilot 17 is burning. Continued heating of the bulb 32 will move the valve member 15 to wide open position.

Now directing attention to Figs. 2 and 4 in particular, the pilot valve indicated at 19 in general comprises a bottom part 100 disposed within the casing and fastened to the bottom parts thereof by means of screws 101. A central projection 102 on this base portion of the valve is disposed in openings in the two parts 51 and 52 of the casing mentioned so as to accurately locate the valve. As best shown by Figs. 4, 7, and 8, this bottom part of the valve has an inlet 103 connected by a threaded coupling 104 to a fuel supply line 105 to the pilot 17. Also this part of the valve has an outlet 106 connected by a threaded coupling 107 to the line 18 previously identified. It may be observed that the coupling 104 extends through an opening in the end wall 65 while coupling 107 extends inwardly above the side flange 67. At its inner end the inlet opening 103

communicates as indicated at 108 with a recess 110 in the upper side of the valve base 100, and this recess at its lower end has a smaller opening or valve port 111 which as best shown by Fig. 4, communicates with an opening 112 leading to the outlet 106.

The upper part of the valve is indicated at 115 and is fastened to the base portion 100 by screws indicated at 116. These two parts of the valve hold a rubber diaphragm 117 over the recess 110, and the diaphragm is sealed at its center to a valve stem 118 which has a lower conical end 119 to meter the flow of gas to the pilot 17 and which is adapted to close the upper end of the opening 111 and thereby interrupt the flow of gas. If the diaphragm and stem are moved upwardly, the gas flows beneath the diaphragm and downwardly through the opening 111 and then through the opening 112 to the outlet line 18.

The valve stem is slidably mounted in a guide element 121 threaded into the upper part 115 of the valve as indicated at 122. This guide terminates at its upper end in a surrounding flange which is a permanent magnet 121^a adjustably locked in position by means of a set screw 123 threaded through said upper part 115 of the valve. Above the magnet 121^a a collar 124 which is the armature cooperable with magnet 121^a, is rigidly connected to the valve stem 118 by means of a pin 125, and this collar has upper and lower flange or disk portions 126 and 127. Movement of this collar upwardly and downwardly carries the valve stem 118 with it and thus will open and close the pilot valve. The upper part 115 of the valve has at its upper side a generally rectangular extension 130 which is interiorly hollow so as to provide a space for the magnet 121^a and armature 124. The valve stem 118 after extending through this hollow or space is slidably mounted at its upper end in a bushing 131. This bushing is threaded downwardly into the upper wall of the extension 130 and a lock nut 132 on the bushing serves to hold it in any adjusted position.

Referring to Figs. 4 and 5, the heat motor 31 comprises a bimetal strip 140 having one end projecting between the two disk portions 126 and 127 on the collar 124 and engaging the underside of the upper portion 126. This end of the strip has a downwardly turned leg 141 adapted to engage the lower disk portion 127 to close the pilot valve 19 if it should stick in open position. The heat motor also includes a strip of electric insulating material 142 disposed on the strip 140 in superimposed relation thereto, a strip of mica 143 disposed on the strip 142, and an upper strip of electric insulating material 144. This assembly is held in laminated relation at one end by a tongue 145 struck from the strip 140 which is bent over in embracing relation to the ends of the other strips.

All four strips are anchored at their other ends on a block of insulating material 148 by means of bolts 150 and 151 extending through the several strips and through the block. The latter has trunnions 152 and 153 at opposite sides which fulcrum in notches 155 and 156 formed in opposite legs 157 and 158 projecting upwardly from a metal strip or supporting member 160. This strip 160 has an opening 161 receiving the upper part 115 of the valve 19, and it is fastened to that part of the valve by means of the screws 116.

The bolts 150 and 151 also extend through a bimetal compensating strip 164 disposed at the bottom side of the block 148 and nuts 165 on

the lower ends of the bolts hold the parts securely in position. For the purpose of releasably retaining the trunnions 152 and 153 in the notches provided therefor, a U-shaped clip 166 embraces the strip 160 and the legs 157 and 158, and upper ends of the clip have inwardly turned lips 168 and 169 which snap over the upper sides of the trunnions. The clip may have additional lips such as indicated at 170 embracing side edges of the legs 157 and 158 so as to properly locate and hold the clip in position.

At its outer or free end the compensating strip 164 is provided with a notch 172 which is engaged by a T-shaped upper end 173 formed on a bracket element 174 anchored on the strip 160 by means of rivets 175. A screw 176 freely extending upwardly through the strip 160 is threaded into the bracket 174, and from this it follows that by adjusting the screw, the strip 164 may be shifted upwardly or downwardly. This adjustment corresponds to adjustment of the strip 68 in the said copending application for patent and is employed to vary the time period required to move the pilot valve to open position. The compensating strip 164 when heated acts to rotate the supporting block 148 to relieve the tension of the heat motor 31 holding the valve 19 open, so that on deenergization of the heat motor the cooling time for closure of the pilot valve will be reduced. The strip 164 is heated by increase of ambient temperature when the heat motor 31 is energized and also by some conduction of heat through the bolts 150 and 151 from the heat motor.

The strip of mica 143 has a heating coil 180 wound about it, and the ends of the coil are electrically connected to the two bolts 150 and 151 which are electrically insulated in any suitable manner from the bimetal strips 140 and 164. The lower ends of the bolts, as best shown by Fig. 5, are connected to wires 181 and 182, and these wires are connected to terminals 183 and 184 on an insulating plate 185 secured by screws 186 to the base portion 53 of the casing. In turn, the terminals 183 and 184 are connected to wires 187 and 188 extending through an opening in the casing, and which are connected to the secondary 30 of the transformer 29.

Now directing attention to Figs. 1 and 2, the inner end 85 of the lever 72 has a link 189 pivotally connected thereto as indicated at 190. This link is pivotally connected as indicated at 191 to a lever or arm 192 having depending ears 193 pivoted as indicated at 194 on an arm 195 projecting upwardly from the portion 130 of the valve 19. The arm 192 at the opposite side of the pivot 194 is reversely bent at its outer end as indicated at 196, and this reverse bend provides a stop for a spring element 197 which is riveted to the arm at a point indicated at 198. This spring element 197 has a nib 199 adapted to engage the upper end of the pilot valve stem 118 and to move it toward closed position to an extent depending upon adjustment of bushing 131 which acts as a stop for engagement by the nib 199.

The device functions as follows. When the room requires heat and the thermostat 24 closes, a circuit is completed through the transformer 22 which energizes the heat motor 31 to stress the free end of the upper bimetal element 140 upwardly against the force of the magnet 121^a when the force of the element 140 overcomes the magnet 121^a, it will bend upwardly and quickly raise the pilot valve stem 118 to open the pilot

valve. Gas is thus supplied to the pilot 17 in sufficient volume to prevent a flash back. Closing of circuit at the thermostat also closes the circuit of the ignition transformer 22 to energize the electrical ignition 20, and it follows that when the gas reaches the pilot it is ignited. As the pilot heats up, the volatile liquid in the bulb 32 expands, and the pressure exerted through the tube 95 collapses the bellows 89 against the action of the spring 94, and this causes the lever 72 to fulcrum clockwise. As the lever fulcrums, it tends to raise the collar 38 and with it the stem 34 and as soon as the force is sufficient to overcome the magnet 42, the main valve opens quickly and gas flows to the main burner 12 where it is ignited by the pilot. After the main valve opens, the armature 40 strikes the roller 41 and further upward movement of the valve is restrained temporarily until the force of the spring 47^a is overcome. Also, the upward movement of the end 85 of lever 72 causes the arm 197 to move and this causes the spring element 197 to move downward and engage the projecting upward end of the valve stem 118 which is now above the bushing 131. Thus any tendency of the main valve to open further, creates a force tending to move the pilot valve stem towards closed position. The continued upward movement of lever 72 moves the pilot valve 19 toward closed position and reduces the flame at the pilot 17. The bushing 131 is adjusted for engagement by the spring 197 to prevent full closure of the pilot valve 19 so as to maintain the pilot flame. The spring 197 provides lost motion so that the lever 72 can have continued main valve opening movement when the pilot valve has been moved by the spring 197 to its minimum open position. The magnet 121^a will not close the pilot valve at this minimum position because of the opposing force of the energized heat motor 31. It will be evident that any reduction in the pilot also reduces the pressure of the volatile liquid against the bellows and any reduction in this pressure on the bellows tends to allow the main valve to move towards closed position, and this in turn reduces the pressure on the pilot valve, so that the heat motor 31 will move the pilot valve toward open position. In fact, the two valves will float or modulate under the counter-acting forces of their respective thermal actuating means until they reach a balanced floating condition with a relatively low pilot flame while the main valve still is fully opened. Variations in this performance can be obtained by adjusting the device 43, as has been brought out in the said copending application for patent, by adjusting the action of the heat motor through adjustment of the screw 176, and by adjusting the bushing 131.

With the main burner now operating and the pilot light also burning with a low flame, the furnace supplies heat until the thermostat 24 is satisfied, and then when the thermostat opens, the circuit through the heat motor is interrupted and this causes the pilot to close and thereafter the bulb 32 cools and finally the main valve closes. The throttling of the pilot valve to provide the minimum flame at the pilot burner which will hold the main valve fully open reduces the cooling time for the bulb 32 when the pilot is extinguished so that the main valve closes more promptly. The term "throttle" or "throttling" as used herein is hereby defined as a reduction in valve opening as distinguished from a complete closing of the valve. The main valve

5 closes sharply, as will be evident from the previous application, after the valve has been moved to the minimum desirable open position where the magnet 42 picks up the armature 40 and snaps the valve closed.

10 With respect to assembly, it is to be observed that the main valve and parts to the left thereof may be mounted on the casing part 51 and that the pilot valve and other parts to the right of the main valve may be assembled separately with the casing part 52. Then the two casing parts may be brought together and connected by the bolts 57 and the screws 101 may then be inserted to lock the pilot valve to both parts of the casing.

15 Although only one form of the invention has been illustrated and described in detail, it will be apparent to those skilled in the art that various modifications may be made without departing from the scope of the claims.

20 What is claimed is:

25 1. An automatic valve assembly comprising a first valve operating stem, a second valve operating stem, a collar fastened on the second stem and having spaced flanges, an electric heat motor having a portion projecting between the flanges, a collar fastened on the first stem and having spaced flanges, a pivoted arm having a portion projecting between the flanges on the collar on said first stem, thermally controlled means for moving the collar on the first stem independently of the second stem, and means on the arm and operatively engageable with the second stem for effecting a closing movement of the second stem upon predetermined valve opening movement of the arm.

30 2. An automatic valve assembly comprising a first valve operating stem, a second valve operating stem, a pivoted arm, means operatively connecting the arm to the first stem for moving it, an electric heat motor, means operatively connecting it to the second stem for moving it, independently of the first stem and means on the arm and operatively engageable with the second stem for reversing operation of the second stem 35 relative to said heat motor upon predetermined opening movement of the first stem, said last means comprising an arm fulcrumed intermediate its ends and having one end disposed for abutting engagement with the end of the second stem and having its other end connected to the first arm.

35 3. In an automatic valve assembly, a first valve member having a stem, a second valve member having a stem, each of said valve members being 40 normally biased toward closed position, an electric heat motor for moving said first valve member toward open position, thermostatic means adapted for response to the extent of opening of said first valve member, said thermostatic means including a movable arm engageable with said second valve stem and operable to move said second valve member toward open position, means 45 limiting opening movement of said second valve member, a lever mechanism operatively connected to said arm and engageable with said first valve stem upon predetermined valve opening movement of said arm and operable upon movement of said arm beyond said predetermined movement to move said first valve member toward closed position, means operable to stop closing movement of said first valve member by said lever mechanism at a predetermined minimum opening for said first valve member, and lost motion means operable to permit continued valve

opening movement by said arm after said first valve closing movement has been stopped.

4. In a burner control system including a main burner and a pilot burner, a pilot valve having a valve stem, a main valve having a valve stem, each of said valves being normally biased toward closed position, an electric heat motor for moving said pilot valve toward open position, said pilot valve being arranged to supply fluid fuel to said pilot burner, a bellows type thermostat having a bulb element responsive to the heat of said pilot burner, a pivoted arm operated by said thermostat and engageable with said main valve stem to move said main valve to open position, a guide member for said pilot valve stem having a lower face operable as a stop to limit upward movement of said pilot valve, a pivoted lever operatively connected to said arm and engageable with said pilot valve stem upon predetermined opening movement of said main valve by said arm, said lever being operable upon engaging movement to move said pilot valve toward closed position to throttle the flow of fuel, said guide member having a portion operable as a stop to limit closing movement of said pilot valve by said lever to a predetermined minimum opening, and said lever having a lost motion spring for transmitting movement to said pilot valve stem and operable to permit overtravel of said lever upon engagement with said guide member so that said main valve may be opened further without further throttling said pilot valve.

5. In a burner control system, a main burner, a pilot burner, a main valve controlling flow of fuel to said main burner, a pilot valve controlling flow of fuel to said pilot burner, automatic means controlling said pilot valve, thermal means variably responsive to the heat output of the pilot flame and controlling operation of said main valve, and means operatively interconnecting said main valve and said pilot valve and operable upon predetermined opening of said main valve to throttle said pilot valve proportionately to the extent of opening of said main valve beyond said predetermined opening.

6. An automatic valve assembly comprising a first valve having an operating stem, a second valve having an operating stem, means for moving said first valve stem, means for moving said second valve stem independently of said first valve stem, said second-named moving means being capable of overpowering said first-named moving means, a lever mechanism positioned to transmit movement from said second valve stem to said first valve stem and movable by said second-named moving means, said lever mechanism being positioned to have a predetermined lost motion relative to one of said valves when both valves are closed and to engage operatively both valves when opened a predetermined amount, and said lever mechanism being operable when moved by said second-named moving means beyond the predetermined opening for said second valve to move said first valve toward closed position.

7. A valve assembly as defined in claim 6 including means limiting movement of said one valve stem in a valve closing direction by said lever mechanism and including means carried on said lever mechanism permitting lost motion of the same relative to said second valve stem beyond the point of limitation of movement thereof.

8. A valve assembly as defined in claim 7 wherein the lost motion means carried on said lever

mechanism comprises a collapsible spring arranged for transmission of movement to said second valve stem and collapsible only upon movement of said lever beyond the point of limitation of movement of said second valve stem.

9. An automatic valve assembly comprising a first valve having an operating stem, a second valve having an operating stem, thermally operated means for moving said first valve stem, means for moving said second valve stem independently of said first valve stem, and means comprising a lever mechanism operatively interconnecting said stems and having lost motion relative to one of them, said lever mechanism being movable by said thermally operated means and upon predetermined movement thereof in a valve opening direction to move said second valve stem in a closing direction in opposition to said second valve stem moving means.

10. An automatic valve assembly comprising a first valve having an operating stem, a second valve having an operating stem, thermally operated means for moving said first valve stem, a pivoted arm for moving said second valve stem independently of said first valve stem, a second pivoted arm arranged to have lost motion relative to said first valve stem and to engage the same in a valve closing direction, and said second arm being arranged for operation by said first named arm.

11. An automatic valve assembly comprising a first valve having an operating stem, a second valve having an operating stem, thermally operated means for moving said first valve stem, an electric heat motor for moving said second valve stem independently of said first valve stem, and means comprising a lever mechanism operatively interconnecting said stems and having lost motion relative to one of them, said lever mechanism being movable by said thermally operated means and upon predetermined movement thereof in a valve opening direction to engage and move said second valve stem in a closing direction in opposition to said heat motor.

12. In a burner control system, a main burner, a pilot burner, a main valve controlling flow of fuel to said main burner, a pilot valve controlling flow of fuel to said pilot burner, automatic means controlling said pilot valve, thermal means responsive to pilot flame and controlling operation of said main valve, and means to throttle said pilot valve upon predetermined opening of said main valve and comprising a lever actuated by said main valve upon predetermined opening movement thereof and movable into valve closing engagement with said pilot valve.

13. In a burner control system, a main burner, a pilot burner, a main valve controlling flow of fuel to said main burner, a pilot valve controlling flow of fuel to said pilot burner, electric means for operating said pilot valve, electric ignition means for igniting fuel at said pilot valve, a circuit including a room thermostat operable to energize simultaneously said valve operating means and said ignition means, and thermal means responsive to the occurrence of flame at said pilot burner and operable to open said main valve, and means to throttle said pilot valve upon predetermined opening of said main valve and comprising a lever actuated by said main valve upon predetermined opening movement thereof and movable into valve closing engagement with said pilot valve.

14. In a burner control system, a main burner, a pilot burner, a main valve controlling flow of

11

fuel to said main burner, a pilot valve controlling flow of fuel to said pilot burner, electric means for operating said pilot valve, electric ignition means for igniting fuel at said pilot burner, a circuit including a room thermostat operable to energize simultaneously said valve operating means and said ignition means, thermal means comprising a heat motor variably responsive to the heat output of the pilot flame and operable directly to open said main valve in proportion to the heat output of the pilot flame, and means operatively interconnecting said main valve and said pilot valve and operable upon predetermined opening of said main valve to throttle said pilot valve proportionately to the extent of opening of said main valve beyond said predetermined opening.

EARNEST J. DILLMAN.
JACK E. FLEURY.
